[57] CLAIM

The ornamental design for a head figure, as shown and described.

DESCRIPTION

FIG. 1 is a front elevational view of a head figure, showing our new design;
FIG. 2 is a rear elevational view thereof;
FIG. 3 is a top plan view thereof;
FIG. 4 is a cross sectional view of FIG. 2;
FIG. 5 is a front elevational view of a second embodiment of the design in FIG. 1;
FIG. 6 is a rear view thereof;
FIG. 7 is a top plan view thereof;
FIG. 8 is a cross sectional view of FIG. 6;
FIG. 9 is an enlarged front view of a third embodiment of the design in FIG. 1, the rear being unornamented;
FIG. 10 is an enlarged front view of a fourth embodiment of the design in FIG. 1, the rear being unornamented;
FIG. 11 is an enlarged front view of a fifth embodiment of the design in FIG. 1, the rear being unornamented; and,
FIG. 12 is an enlarged front view of a sixth embodiment of the design in FIG. 1, the rear being unornamented.
